UNITED STATES PATENT OFFICE

DONALD A. McLAUGHLIN, OF JANEVILLE, WISCONSIN, ASSIGNOR TO THE PARKER PEN COMPANY, OF JANEVILLE, WISCONSIN, A CORPORATION OF WISCONSIN

FOUNTAIN PEN

Application filed October 9, 1929. Serial No. 398,317.

My invention relates to "self-filling" fountain pens of a character having an ink sack collapsible by pressure-bar mechanism actuated by endwise pressure against a plunger or button located at the end of the pen barrel opposite the pen-section.

Heretofore, it has been customary in fountain pens of this character, to compress the ink sack by means of a pressure bar carried 10 by a flat resilient member or spring, the lower end of which abuts against the pen-section for support of the same against endwise movement when the end-mounted plunger or button is pressed endwise. Such spring 15 bows inwardly when the plunger or button is pressed inwardly thereby moving the pressure-bar inwardly to collapse or deflate the ink sack and the spring straightens out when the plunger or button is released permitting 20 the ink to be sucked into the sack. With such arrangement, the pen section must be screwed into, or otherwise positively secured, to the barrel to prevent the same from being loosened or ejected by the pressure exerted 25 against it in the collapsing of the sack.

The foregoing construction is subject to certain objections and disadvantages, some of which are: The pen point section and barrel must be provided with threads which add 30 materially to production costs; the parts must be made and fitted with a high degree of nicety to assure that the pressure bar supporting spring will properly abut the pen section so that such spring will be normally 35 unbowed and will, at all times, be bowed the proper extent to fully deflate the sack; the pen barrels may shrink after being placed on the market thereby upsetting the originally-provided relationship between the 40 above-mentioned fitted parts of the pen; the ink sack is supported by the pen section and the lower end of the pressure bar supporting spring contacts with the ink sack tending to 45 chafe the same and hasten its deterioration; and the ink sack being supported by the pen section, rotates with the pen section when the latter is screwed into the barrel during which 50 the pressure bar mechanism which, unless

remedied, hinders the normal functioning of the sack.

The principal object of my invention is to overcome the foregoing disadvantages and objectionable features existent in fountain pens of the character particularly referred to; and, to that end, my invention generally contemplates the provision of a supporting device for the lower end of the resilient member or pressure bar supporting spring, which 55 does not contact or depend for support, or function, upon the pen section.

A more specific object of my invention is the provision of a sleeve-form of abutment 60 mounted within the barrel independently of the pen section and of a form adapted to be permanently fixed within the barrel to provide an abutment and a retaining space for the lower or inner end of the spring so that 65 such end, while positively confined, neither 70 engages the sack or the pen section. With such arrangement the pen section may be slip-fitted into the barrel; shrinkage of the 75 parts after the pen is in the hands of the user will not affect the operation of the pen; the spring member does not have a deteriorating effect upon the ink sack; the ink sack and pen section may be inserted within the barrel by an endwise, non-rotatable movement so that the ink sack will not become 80 twisted and will, at all times, deflate normally; and a simple, inexpensive and easily 85 assembled and disassembled pen structure is provided.

A further object of my invention is to provide a novel form of sleeve abutment for supporting and receiving the lower end of the 90 spring member, which abutment of itself is arranged to coact with the pen barrel to prevent shrinkage of the latter to maintain a predetermined spacing between a portion of the sleeve and the barrel providing at all times a proper receiving-supporting space for the lower or inner end of the spring member. 95 More particularly, my invention contemplates, specifically, the use of a sleeve-type abutment having one part adapted to be locked within a suitable groove in the pen barrel; another part of a diameter substan- 100

tially equal to the inside diameter of the pen barrel so as to fit snugly thereagainst for the above shrinkage resistance; and another part of still further reduced dimensions providing 5 between the same and the barrel wall a space for receiving the end of the spring member.

Other objects and advantages will become apparent as this description progresses and by reference to the drawing wherein,—

10 Figure 1 is a partial sectional view of a fountain pen embodying my invention;

Fig. 2 is a perspective view of the pressure bar mechanism shown in Fig. 1;

15 Fig. 3 is a fragmental view, partially in section, showing the relationship between the pressure button and the pressure bar supporting spring; and

Fig. 4 is a perspective view of the sleeve abutment shown in Fig. 1.

20 Referring particularly to the drawing, the form of fountain pen structure illustrated includes a barrel 10 which supports at its lower end a pen-section comprising a nozzle 11, feed bar 12 and nib 13. This barrel is, preferably, 25 formed of hard rubber, pyralin or other similar material. The cylindrical end part 11^a of the nozzle is of reduced diameter and has a snug, tight slip-fit with the lower end of the barrel. The extreme inward end part 11^b of 30 this nozzle is still further reduced in diameter and receives the open end of the ink sack 14 in a manner well understood.

35 Filling of the sack 14 with ink is accomplished by means of a bowable spring member 15 and pressure bar 16 which rests flat against the ink sack for collapsing the latter substantially throughout its length as the spring 15 is bowed. This mechanism is supported and actuated in the following manner: 40 The upper or rear end of the pen barrel is provided with a reduced threaded neck 17 having a central opening 18 in which is mounted a hollow plunger 19 provided with a pressure button 19^a on its outer end. The 45 lower or inner end of this plunger is slotted providing a plurality of resilient fingers 20 having at their ends shoulders or flanges 21^a normally limiting outward movement of the plunger, but permitting the plunger to be 50 withdrawn through the opening upon sufficient pressure being applied thereto to compress the fingers 20. The pressure bar supporting spring 15, adjacent its rear or upper end and beyond the rear end of the ink sack 55 14, is turned diagonally inward and then outwardly so that its extreme rear end passes into and is seated within the plunger 19 as clearly shown in Fig. 3.

60 My invention has to do mainly with the provision of supporting means for the lower or forward end of the spring member 15 which is independent of the pen section 11 so that upon inward movement of the button 19, the spring will be bowed and the pressure bar 16 moved inwardly to deflate

the ink sack. To this end, I provide a sleeve member 22 (Fig. 4) which is provided with three different-diameter sections. The larger-diameter section 22^a is adapted to seat in a groove 23 formed in the inner barrel wall above the inward end of the pen section 11. The sleeve section 22^b is of lesser outside diameter than the section 22^a and is of the internal diameter of the pen barrel so that it fits snugly against the barrel wall. 70 The section 22^c is of lesser diameter than the inside diameter of the pen barrel thereby providing a space for receiving the lower end of the spring member 15 and also providing at its junction with the section 22^b 75 a shoulder 24 upon which the end of the spring member 15 seats.

80 In assembling the sleeve abutment member 22, the inner wall of the barrel, before the barrel is finally cured or seasoned, is first 85 grooved at the proper place and the sleeve is then forced into the barrel until its larger diameter section 22^a seats in the groove 23. Although this larger diameter section 22^a is 90 slightly larger than the inside diameter of the barrel, the resiliency of the material from which the barrel is formed permits of sufficient yielding of the same to permit the sleeve to be forced into place as stated. After the sleeve is inserted in the barrel, the barrel is then put through the usual final curing or seasoning process which serves to 95 further tighten the barrel around the sleeve, thus permanently locking it into place. The sleeve section 22^b which snugly fits against 100 the inside wall of the pen is of sufficient length to provide a substantial support for the adjacent barrel wall surface and this section maintains proper clearance between the sleeve section 22^c and the barrel wall regardless of shrinkage tendency in the barrel so as to provide at all times a space for freely receiving and confining the lower end of the 105 spring member 15.

110 It will be noted that the sleeve section 22^c, together with the pen wall, provides a spring-end receiving-space extending entirely around the barrel wall. This arrangement 115 insures proper positioning of the pressure bar structure, as a complete unit, in any position which the barrel may assume during assembly so that the ink sack will not be injured and it will always be properly acted upon by the pressure bar. The extreme inward or lower end of the spring member 15 is curved or dished as at 15^a to conform somewhat to the curvature of the pen barrel so that this end of the spring will fit freely in its curved retaining space and will properly abut the shoulder 24.

120 From the foregoing, it will be obvious that with the parts assembled as shown in Fig. 1, endwise pressure on the plunger 19 will bow the spring member 15 inwardly and move the pressure bar 16 to collapse or de- 125

flate the ink sack 14. Upon releasing the plunger 19, the spring member 15 will return to its normal straight condition and the sack will quickly return to its normal expanded position resulting in the ink being sucked thereinto in a manner which will be well understood. No pressure is exerted on the pen section by the above filling operation and the pen section may readily be slipped 10 fitted into the lower end of the barrel with its attendant advantages as hereinabove more particularly mentioned. The lower end of the spring member 15, being confined by the sleeve 22, does not contact with the ink sack 15 and injure the same. Shrinkage is immaterial insofar as the operation of the filling mechanism is concerned.

It will be understood that while I have shown only one form of my invention, other 20 changes in details and arrangement of parts may be made without departing from the spirit and scope of my invention as defined by the claims which follow.

I claim:

1. The combination with a fountain pen having a barrel, a pen section, an ink sack, and a pressure bar for deflating the sack, of abutment means fixed within said barrel independently of the pen section, and providing 25 a confined space around the pen barrel with a shoulder at its bottom, a resilient member supporting said bar and having its one end loosely seated in said space against said shoulder, and means engaging the other end 30 of said resilient member for exerting end-wise pressure thereon to bow the same to deflate said sack.

2. In a fountain pen of the character described, a barrel having a groove therein, and 40 filling mechanism mounted in said barrel and including a sleeve member having one portion fitting said groove, another portion fitting the inner wall of the pen and of substantial length to support the barrel wall 45 against shrinkage at that point, and another portion of lesser diameter forming with the barrel wall a space for confining another portion of said filling mechanism.

3. In a fountain pen of the character described, a barrel having a groove therein, and filling mechanism mounted in said barrel and including a multidiameter sleeve member, one diameter thereof fitting said groove, another and lesser diameter fitting 55 the internal wall of the barrel, and another and still further reduced diameter which with the internal barrel wall forms a confining-supporting space for receiving another part of the filling mechanism.

4. In a fountain pen, the combination with 60 a barrel, a collapsible ink sack in said barrel, and a pressure bar engaging said sack, of a flexible support member for said pressure bar, means for loosely confining one end 65 of said member against lateral displacement

and also affording an abutment for that end of said member to prevent end-wise movement of the same, and means acting on the other end of said member to exert end-wise pressure thereon to bow said member.

5. In a fountain pen, the combination with a barrel, a collapsible ink sack in said barrel, and a pressure bar engaging said sack, of a flexible support member for said pressure bar, a sleeve-like device fixed in said barrel and so shaped as to provide in conjunction with the barrel a space for loosely confining one end of said member against lateral displacement and also affording an abutment for that end of said member to prevent end-wise movement of the same, and means acting on the other end of said member to exert end-wise pressure thereon to bow said member.

6. In a fountain pen, the combination with a barrel having an opening in one end, a pen section mounted in its other end, an ink sack therein, and a pressure bar acting on said sack, of a flexible support member for said bar, and means in said barrel independent of said pen section for loosely confining one end of said member and providing an abutment therefor, said member being accessible through said barrel opening for ready and free removal of the same, said means operatively receiving said one end of said member regardless of the position of barrel when said member is inserted therein through said end opening.

7. In a fountain pen having a barrel with a groove in its inner wall, an ink sack therein, and filling mechanism including a pressure-bar and a flexible support therefor, a confining-abutment member for one end of said member which is of sleeve form having one part fitting said barrel groove, a second part fitting the inner barrel wall, and a third part lesser in diameter than the other parts forming with said barrel wall a space extending around the barrel wall, and the juncture of the second and third parts forming a shoulder providing an abutment for the end of said member freely received and confined in said space.

8. An abutment device for the purpose described which takes the form of a sleeve having one part adapted to be permanently secured in the inner wall of the pen barrel, another part adapted to seat against and brace the barrel wall, and another part of lesser diameter than the barrel wall to provide with the wall an annular retaining space having an abutment surface at its bottom.

9. An abutment device for the purpose described which takes the form of a sleeve having one diameter part less than the inside diameter of the pen barrel, another and adjacent diameter part of the substantially inside diameter of the pen barrel, and another

diameter part greater than the inside diameter of the pen barrel.

- 5 10. In a fountain pen, the combination with a barrel, an ink sack therein, filling mechanism which includes a flat bowable spring member and which is insertable in and removable as a unit, from the barrel, of abutment confining means mounted in said barrel independently of the pen section and which is adapted to provide a space freely receiving one end of said spring member at any position such end may assume along the pen barrel when the filling mechanism is inserted in the barrel.
- 15 20. 11. In a fountain pen, the combination with a barrel, an ink sack therein, filling mechanism which includes a flat bowable spring member and which is insertable in and removable, as a unit, from the barrel, and a pen section of a sleeve member mounted in said barrel independently of the pen section and which is formed to provide a space freely receiving one end of said spring member at any position such end may assume along the pen barrel when the filling mechanism is inserted in the barrel, which sleeve member also provides an abutment for said member end to prevent bodily end-wise movement of said member.
- 25 30. In testimony whereof, I have subscribed my name.

DONALD A. McLAUGHLIN.
